UNITED STATES PATENT OFFICE.

JOHN JAMES ABELL AND CLARENCE BEN GIFFORD, OF COLESBURG, KY.

PRIMARY ELECTRIC CLOCK.

SPECIFICATION forming part of Letters Patent No. 360,078, dated March 29, 1887.

Application filed November 27, 1886. Serial No. 220,074. (No model.)

To all whom it may concern:

Be it known that we, JOHN JAMES ABELL and CLARENCE BEN GIFFORD, citizens of the United States, residing at Colesburg, in the county of Hardin and State of Kentucky, have invented new and useful Improvements in Electric Clocks and Electric-Clock Systems, of which the following is a specification.

Our invention relates to improvements in electric clocks and electric-clock systems; and it consists in the circuit including the secondary clocks and the primary clocks having the devices to close the said circuit at suitable regular intervals of time.

15 It further consists in the combination, in a clock, of the escapement-wheel, the anchor, and the spring to move the escapement-wheel during the interval when it is disengaged by the points of the anchor.

20 Our invention further consists in the peculiar construction and combination of devices, that will be more fully set forth hereinafter, and particularly pointed out in the claims.

In the accompanying drawings, Figure 1 is 25 a diagram of an electric-clock system embodying our improvements, in which the circuits are traced. Fig. 2 is an elevation of a primary clock embodying our improvements, parts of the dial being broken away to disclose interior 30 mechanism. Fig. 3 is an elevation, partly in section, of our improved clock mechanism. Fig. 4 is a top plan view of the same, partly in section.

a represents the arbor of the primary clock 35 A, which carries the second-hand b. To the said arbor is rigidly attached an escapement-wheel, c, having thirty teeth.

d represents a ratchet-wheel, which is loosely mounted on the arbor a, and is also provided 40 with thirty teeth. The front end of the arbor a extends through a hollow spindle, e, that projects from the front side of the frame in which the clock mechanism is mounted. A coiled hair-spring, f, has its inner end attached to the arbor a, and its outer end attached 45 to the ratchet-wheel, and thereby, when the ratchet-wheel is rotated in the direction indicated by the arrow in Fig. 3 and independently of the arbor a, the spring will be coiled or 50 wound. A gravity-pawl, g, is pivoted to a fixed point and engages the ratchet-wheel, so as to prevent retrograde rotation thereof.

Near one end of the arbor a is a pinion, h, which meshes with a gear-wheel, i, on a shaft, k, the said shaft being connected to the hollow sleeves that carry the minute and hour hands by suitable gear-wheels, which need not be more particularly described herein, as they are of the usual construction and arrangement.

Attached to the clock-frame is an electro-magnet, l, and journaled in the said frame is a rock-shaft, m, carrying an armature, n, that is opposed to the poles of the electro-magnet. The vibration of the armature is limited by adjustable stops n' and n''. Pivoted to the 65 armature is a gravity-pawl, o, that also engages the ratchet-wheel. An anchor, p, is attached to the armature and is vibrated thereby, the said anchor having the points p' and p'' to engage the teeth of the escapement-wheel.

A retracting-spring, r, is adapted to draw the armature from the magnet when the latter is demagnetized, and a tension device, s, is provided to regulate the strength of the said spring.

The ratchet-wheel d has on one side a projecting contact-point, t, that is adapted to contact with a point, u, once at each rotation of the said ratchet-wheel. The point u is carried by the anchor and moves therewith, and is 80 within the path of the point t when the armature is attracted by the electro-magnet. The points t and u form the terminals of the circuit v, in which is included the electro-magnet w of one or more secondary clocks, B. A battery, x, or other suitable source of electricity, is also included in the circuit v.

The secondary clocks are similar in construction to the primary clocks hereinbefore described, with the exception that the minute-hands thereof are so geared to the armatures of their electro-magnets that the said hands will be moved on their dials through the space, indicating a minute every time that their armatures are attracted.

It will be of course understood that the secondary clocks are not provided with second-hands, and hence do not mark intervals of time less than one minute in duration.

C represents a pendulum such as described 100 in Letters Patent of the United States No. 351,239, granted to us October 19, 1886. This pendulum swings once every second, and is adapted at each vibration in one direction to

close the circuit z , which includes the battery a' and the electro-magnet of the primary clock.

- The operation of our invention is as follows:
- 5 When the circuit z is open, at each alternate movement of the pendulum the spring r retracts the armature, thereby moving the anchor against the stop n and causing the point p' to engage a tooth of the escapement-wheel.
- 10 When the pendulum swings in the contrary direction during the ensuing second of time, the circuit z is closed, the cores of the electro-magnet l are magnetized, and the armature n attracted thereby, thus causing the point p' to 15 disengage the tooth of the escapement-wheel with which it is in contact, thereby releasing the escapement-wheel, and causing the hair-spring f , in its natural tendency to uncoil, to move the escapement-wheel in the direction indicated by the arrow in Fig. 3 a distance corresponding to one-half a tooth, when it is engaged by the point p^2 of the anchor. The pawl g prevents the ratchet-wheel from retrograding while the pawl o is slipping back on 25 the same when the armature is attracted. At the ensuing stroke of the pendulum, when the circuit z is broken, the armature is retracted by the spring r , and causes the pawl o to turn the ratchet-wheel d loosely on the arbor a in 30 the direction opposite that indicated by the arrow in Fig. 3 a distance corresponding to half a tooth, while the escapement-wheel is held fast, thus winding the hair-spring sufficiently to compensate for the slight previous uncoiling action thereof, hereinbefore described, and consequently preserving the tension of the spring f , so that its strength will be at all times sufficient to propel the train. At each stroke of the pendulum the second-hand of the primary clock is moved over the dial a corresponding distance, and as the gears which actuate the hour and minute hands are connected with the second-hand arbor a , as shown and hereinbefore stated, it follows that the 40 said hour and minute hands will be correspondingly moved on the dial. At each complete revolution of the ratchet and escapement wheels of the primary clock, which occurs every minute, the point t , which is carried by 45 the ratchet-wheel, comes in contact with the point u and closes the circuit v , thereby causing the electro-magnets of the secondary clocks to be magnetized and attract their armatures, and thus move their hands through a 50 space on the dials corresponding to a minute of time. This causes the primary and secondary clock mechanisms to move synchronously.
- The primary clock is provided with the second-hand moved synchronously with the pendulum, in order that any inaccuracies may be 55 noted and the pendulum regulated by the

means described in our before-mentioned Letters Patent, so as to cause the system of clocks to indicate precisely the correct time.

65

The loose ratchet-wheel on the arbor a and the hair-spring connecting the said ratchet-wheel to the said shaft cause the escapement-wheel to be positively impelled at each movement of the anchor, so that it will be impossible for the points or teeth of the anchor to fail to move the escapement-wheel, and thus impair the accuracy of the clock.

70

We do not desire to limit ourselves to the precise construction hereinbefore described, 75 as it is evident that modifications may be made therein without departing from the spirit of our invention.

80

Having thus described our invention, we claim—

1. In the escapement mechanism of a clock, the combination of the escapement-wheel, the anchor, the ratchet-wheel free to move independently of the escapement-wheel, the pawl movable with the anchor and engaging the ratchet-wheel, the detent to prevent retrograde movement thereof, and the spring connecting the ratchet-wheel and the escapement-wheel to move the latter during the instant that it is disengaged by the anchor, substantially as described.

85

2. In the escapement mechanism of a clock, the combination of the escapement-wheel, the anchor, the rotating wheel d , independent of the escapement-wheel, and the spring connecting the said wheel d and the escapement-wheel to move the latter during the instant it is disengaged by the anchor, substantially as described.

95

3. In a primary electric clock, the combination of the anchor, the escapement-wheel movable by the anchor, and the spring r ; and electro-magnet to operate the latter, the ratchet-wheel d , independent of the escapement-wheel and having the contact-point t , forming the terminal of the electric circuit, the detent to prevent retrograde rotation of the ratchet-wheel, the pawl carried by the anchor and engaging the ratchet-wheel, the spring connecting the ratchet-wheel and the escapement-wheel, for the purpose set forth, and the vibrating point u , carried by the anchor and forming the other terminal of the circuit, and adapted to come in contact with the point t at regular intervals of time, for the purpose set forth, substantially as described.

100

In testimony that we claim the foregoing as our own we have hereto affixed our signatures in presence of two witnesses.

JOHN JAMES ABELL.
CLARENCE BEN GIFFORD.
